ANIMATED DISPLAY OR SIGN APPARATUS

James T. Mullen, Cleveland, Ohio, assignor to
The Dymont Company, Cleveland, Ohio, a cor-
poration

Application February 13, 1934, Serial No. 711,054

18 Claims. (Cl. 40—130)

The present invention has to do primarily with advertising displays or signs and involves the employment of sign or display features in which light rays are caused to produce moving light effects upon a main display member forming a part of the apparatus.

An especial object of this invention is to avail of reflected light from a source of light to throw reflected images upon the main sign or display member, said images to be transmitted consecutively to the main sign member, in a simple form of the invention, in a continuous moving manner, so to speak. In another embodiment of the invention, carrying out the general principle of utilizing the projection of reflected images to the main sign member, a multiplicity of such reflected images may be produced by the employment of one or more supplemental reflectors for transmitting reflected light rays from the source of light to the main sign member.

In all forms of my apparatus there are employed at least three principal parts, namely, a source of light, a main sign member to which the rays of light may be passed and constituting a reflection receiving member in the practical operation of the invention, and thirdly, a reflecting sign member positioned properly in relation to the reflection receiving member so that the rays of light transmitted to the reflecting sign member may be caused to produce the image of the reflecting sign member upon the main reflection receiving member. When multiple reflections are to be resorted to, there will be added the supplemental reflectors which are preferably arranged on the side of the reflection receiving member opposite that at which the reflecting sign member is disposed, and by the peculiar arrangement of the supplemental reflectors, variations in the kind and shape and size of the reflections caused to be produced upon the reflection receiving member are obtainable.

In addition to its function as a reflecting means, the reflecting sign member employed constitutes a curtain member, so to speak, for hiding the source of light availed of thus preventing the direct rays from the source of light from reaching the eyes of the person or persons who view the display apparatus in actual use.

A full comprehension of the construction of the display inventions hereof and the mode of use of the same under practical conditions will be had upon reference to the annexed drawings, in which—

Figure 1 is a front elevation of a simple form of the invention.

Figure 2 is a top plan view of the construction of Figure 1.

Figure 3 is a vertical sectional view through the apparatus shown in Figure 1.

Figure 4 illustrates a detail involving the flap or shelf member which projects from and may or may not be formed with the reflection receiving member for facilitating the proper positioning of the reflecting sign member in relation to the reflection receiving member.

Figure 5 is a detail fragmentary perspective showing more fully the parts of Figure 4 after they have been folded and placed in operative position ready to receive the vertically disposed reflecting sign or display member.

Figure 6 is a top plan view similar to Figure 2 but illustrating a modified embodiment of the invention availng of supplemental vertical and horizontal reflectors, the vertical reflector in rear of the light source and the horizontal reflector beneath the light source.

Figure 7 is a vertical sectional view similar to Figure 3 but illustrating the modification of Figure 6.

Figure 8 is a detail view in elevation of the light source and moving screen apparatus carried thereby.

Figure 9 is a top plan view of the screen frame as shown in Figure 8.

Figure 10 is a detail fragmentary view of the lower end portion of the reflecting sign member showing the notches that are adapted to interlock with the notches on the offstanding flap or shelf member seen best in Figures 4 and 5.

The display of this invention is of relatively simple construction, including the reflection receiving sign or member 1 preferably, though not necessarily, formed with the wings 2 facilitating the setting up of the member 1 in a standing position as shown. The member 1 is preferably formed with an opening 3 and in rear of this opening is positioned the light source consisting of an incandescent lamp shown in dotted lines in Figure 3 and designated 5. Upon this lamp or light 5 is mounted a screen frame 6 carrying a series of differently colored screens 7 for a purpose to be hereinafter set forth. The screen frame 6 and screens 7 are capable of rotation upon a vertical axis supported by the light or lamp 5 and the rising gases from the heat of the light source 5 coating with the vanes 8 on the top of the screen frame 6 cause the continuous rotation of the screens 7 in a manner well known to those versed in this art.

Preferably, though not necessarily, formed as

a part of the lower portion of the member 1, is a flap or extension 9 scored so that it may be folded to a position at right angles to the member 1 as shown in Figure 5 and equipped at its edges with the upwardly folded flanges 10 formed with one or more notches 11, these notches facilitating the positioning in spaced relation to the member 1 of a reflecting sign member 12. The sign member 12 is designed to be of any suitable outline, having in view purposes of advertising a particular subject. The sign member 12 illustrated in the drawings, especially Figure 1, is representative of the earth or globe illustrative of the world, and at the top of this sign member is a cut-out extension illustrative of a can or bucket 12a, the contents of which are seemingly being poured upon the depicted globe. The inner or rear face of the reflected sign member 12 designated 12b bears a reflecting surface. At its lower edge portion the sign member 12 is formed with notches 12c to engage in opposite notched portions 11 on the shelf-like member 9, the cooperation being such that the part 12 may be adjustably positioned in relation to the part 1 in a self-evident manner.

Describing the animated action of the sign apparatus thus far set forth in conjunction with Figures 1 and 3 particularly, it is notable that the colored screens 7 in their movement are interposed between the source of light 5 and the reflected sign member 12. Light rays are projected therefore directly from the light source through the screen members 7 upon the reflecting surface 12b, and this produces upon the front of the reflection receiving member 1 the reflected image or outline of the reflected sign member 12. The size of the image produced depends upon the distance apart of the two members 1 and 12. Since the screen members 7 are of different colors, during the rotation of the screen frame 6 the reflected image produced by the sign 12 upon the reflection receiving surface of the member 1 changes in color, as for instance from blue to green to yellow, to red, etc. as these particular colors of the screens 7 pass between the light source 5 and the reflecting sign member 12, and the colored rays are projected to the reflecting surface 12b on the reflecting back and therefrom to the front reflection receiving surface of the member 1.

As intimated above, the reflected images produced upon the reflection receiving member 1 in the above manner are received consecutively, and because of the changing colors, animation is imparted to the sign apparatus in an obvious way, and the colored effects of the reflection produced upon the member 1 afford interesting and attractive changes. During the production of the reflected images upon the member 1, the member 12, as previously suggested herein, constitutes a curtain or cut-off preventing the direct rays of light from passing from the light source to the observer or looker-on.

Referring now to Figures 6 and 7, an extension of the principles of the invention is carried out by utilizing reflectors supplemental to the reflecting surface 12b previously referred to. In this particular construction there is availed of a base or horizontal reflector 13, the top surface of which is of a reflecting nature, and additionally may be provided the supplemental reflector 14 having the reflector wings 15 and 16, said reflectors 14, 15, and 16 having the reflecting surfaces 14a, 15a, and 16a respectively. Now it will be evident from the illustrations of Figure 6

that by the employment of the supplemental reflector 13 light rays will be directly projected to the base reflector 13 and from said reflector to the vertical reflecting surface of the reflecting sign member 12. The reflections produced from the base member 13 in this manner may be multi-colored because colors of different screens 7 may be projected at the same time to and from the upper reflecting surface of the reflector 13. In like manner it is notable that if one or more of the reflectors 14, 15, or 16 are used, the light rays from the source of light 5, rearwardly through the screens 7, will be received upon the reflecting surfaces of the last mentioned reflectors and then projected from said surfaces to the reflector surface 12b and back upon the reflection receiving member 1. The base reflector 13 may be used without the reflectors 14, 15, and 16, or the reflectors 14, 15, and 16 may be used without the reflector 13, or only one of the reflectors 14, 15, and 16 used with or without the reflector 13, dependent upon the particular effects to be secured, preferably in the display apparatus, and dependent upon the nature of the advertising or display to be produced. It is evident that multi-colored reflected images may be readily projected upon the reflection receiving member 1 by the use of the multi-reflector arrangements above described, and in the use of apparatus of Figures 6 and 7, the colored effects and the animation effects obtained will be multiplied materially as respects the simple form of my invention of the constructions of Figures 1, 2 and 3. Many different animated effects may thus be produced in the multi-reflector type of construction that cannot be obtained in the simple construction of Figures 1 to 3 and among these multi-reflection effects are involved effects of animation produced by reflected images produced on the reflection receiving member 1, which images merge one into the other after a manner, or are seemingly superposed one upon the other after a manner when viewed in the practical operation of the invention.

In Figure 1 there is depicted the effect of the reflected image designated A and A' of the reflection produced by the sign member 12 upon the member 1. This reflected image is in color because of the use of colored screen means interposed between the source of light and the reflecting surface 12b. Because of the movement of the screens, the reflected images A and A' have the effect of animation, for obvious reasons. In like manner, though not illustrated, while as to the construction of Figures 1 and 3 apparatus, the reflected images A and A' are produced in a continuous and consecutive order, when the apparatus of Figures 6 and 7 is employed, the effect of the movement of the screens and various reflected and direct light rays passing to the reflector surface 12b is to cause merging of different colored reflected images projected upon the receiving member 1, and to some extent these images superpose upon one another with life-like movement effects. Those parts in Figures 6 and 7 which are like the corresponding parts of the apparatus of Figures 1 and 3 are similarly designated.

It is to be understood that within the purview of my invention I do not wish to be limited to any particular construction of mounting means for the screen 7 because these screens could be caused to be moved by any suitable kind of motor, employed in any suitable number, carried by an endless belt or like carrier and disposed in various

relative positions as respects the several reflectors described. The angularity of the disposition of the reflectors 15 and 16 may be varied in relation to the light source and in relation to the reflector 5 14 as well as the base reflector 13 if the latter be used. Likewise, the size of the image produced may be changed by adjustment of the reflected sign member 12 relatively to the reflection receiving member 1 as set forth.

10 This invention contemplates also a method of producing animated effects in display apparatus involving the peculiar projecting of light rays from a light source to a reflecting surface and from thence to a reflection receiving surface combined with other light rays projected from the light source to a reflector from which they are transmitted to the reflection receiving member to pass to the reflection receiving member, and coloring said light rays as they pass from the light source to 20 the various reflecting parts so that the colored effects are ultimately transmitted to the reflection receiving member.

Having thus described my invention, what I claim as new and desire to secure by Letters Patent of the United States, is—

1. In an animated display of the class described, in combination, a reflection receiving member having an opening therethrough, a reflecting sign member spaced therefrom and provided with a reflecting surface facing the reflection receiving member, and a light source disposed on the side of the reflection receiving member opposite that at which the reflecting sign member is disposed so that the rays of light from the light source may be projected to the reflecting surface of said sign member through the reflection receiving member opening and projected from such surface upon the adjacent face of the reflection receiving member.

40 2. In an animated display of the class described, in combination, a reflection receiving member, a reflecting sign member for producing a reflection upon the receiving member aforesaid and spaced therefrom, and a light source arranged so that rays may be projected therefrom to a reflecting surface of the reflecting sign member, said rays to be thereby projected upon the reflection receiving member, the reflection receiving member being provided with an opening through which the rays of the light source may pass to the reflecting surface of the reflecting sign member.

3. In an animated display of the class described, in combination, a reflection receiving member, a reflecting sign member for producing a reflection upon the receiving member aforesaid and spaced therefrom, and a light source arranged so that rays may be projected therefrom to a reflecting surface of the reflecting sign member, said rays to be thereby projected upon the reflection receiving member, the reflection receiving member being provided with an opening through which the rays of the light source may pass to the reflecting surface of the reflecting sign member, and a colored screen interposed between the light source and the reflecting sign member.

4. In an animated display of the class described, in combination, a reflection receiving member, a reflecting sign member spaced therefrom and provided with a reflecting surface facing the reflection receiving member, a light source disposed on the side of the reflection receiving member opposite that at which the reflecting sign member is disposed, said reflection receiving member having means for permitting the rays of light from the light source to be projected to the reflecting sur-

face of said sign member and projected from such surface upon the adjacent face of the reflection receiving member, and moving differently colored screens interposed between the light source and the reflecting surface of the reflecting sign member. 5

5. In an animated display of the class described, in combination, a reflection receiving member, a reflecting sign member spaced therefrom and provided with a reflecting surface facing the reflection receiving member, a light source disposed on the side of the reflection receiving member opposite that at which the reflecting sign member is disposed so that the rays of light from the light source may be projected to the reflecting surface of said sign member and projected from such surface upon the adjacent face of the reflection receiving member, and moving differently colored screens interposed between the light source and the reflecting surface of the reflecting sign member, the reflection receiving member being formed with an opening through which the light rays pass from the light source through the said receiving member to the said reflecting surface of the sign member. 25

6. In an animated display of the class described, in combination, a reflection receiving member, a reflecting sign member spaced therefrom and provided with a reflecting surface facing the reflection receiving member, a light source disposed on the side of the reflection receiving member opposite that at which the reflecting sign member is disposed so that the rays of light from the light source may be projected to the reflecting surface of the sign member and projected from such surface upon the adjacent face of the reflection receiving member, and moving differently colored screens interposed between the light source and the reflecting surface of the reflecting sign member, the reflection receiving member being formed with an opening through which the light rays pass from the light source through the said receiving member to the reflecting surface of the sign member, the reflecting sign member being of a size to form a curtain cutting the direct light rays projected from the light source through said opening, and the reflection receiving member being formed with a shelf-like support having interlocking connection with the sign member. 45

7. In an animated display of the class described, in combination, a reflection receiving member having an opening, a reflecting sign member disposed at one side of said receiving member for producing a reflection upon the receiving member aforesaid and spaced therefrom, a light source disposed on the opposite side of said receiving member arranged so that rays may be projected therefrom passing through the opening to a reflecting surface of the reflecting sign member, said rays to be thereby projected upon the reflection receiving member, supplemental reflector means cooperating with the light source to receive light rays therefrom and reflect such rays to the reflecting surface of the reflecting sign member, and a moving colored screen interposed between the light source and the reflecting sign member and between said light source and said supplemental reflector. 60

8. In an animated display of the class described, in combination, a reflection receiving member having means for permitting light rays to pass therethrough, a reflecting sign member disposed in spaced relation at one side of said receiving member for producing a reflection upon the receiving member aforesaid, a light source arranged 75

- at the opposite side of said receiving member so that rays may be projected therefrom through the receiving member to a reflecting surface of the reflecting sign member, said rays to be thereby projected upon the reflection receiving member, supplemental reflector means cooperating with the light source to receive light rays therefrom and reflect such rays to the reflecting surface of the reflecting sign member, and a series of differently colored moving screens arranged to move between the light source and the reflecting surface of the sign member and between the light source and the reflecting surface of the supplemental reflector means.
9. In an animated display of the class described, in combination, a reflection receiving member having an opening for passing light rays, a reflecting sign member disposed at one side thereof in spaced relation to said receiving member for producing a reflection upon the receiving member aforesaid, a light source arranged at the opposite side of said receiving member so that rays may be projected therefrom through said opening to a reflecting surface of the reflecting sign member, said rays to be thereby projected upon the reflection receiving member, and supplemental reflector means cooperating with the light source to receive light rays therefrom and reflect such rays to the reflecting surface of the reflecting sign member, said supplemental reflector means comprising a series of reflectors parallel with the sign member in one plane and disposed at angles in relation to each other.
10. In an animated display of the class described, in combination, a reflection receiving member, a reflecting sign member for producing a reflection upon the receiving member aforesaid and spaced therefrom, a light source arranged so that rays may be projected therefrom to a reflecting surface of the reflecting sign member, said rays to be thereby projected upon the reflection receiving member, supplemental reflector means cooperating with the light source to receive light rays therefrom and reflect such rays to the reflecting surface of the reflecting sign member, said supplemental reflector means comprising a series of reflectors parallel with the sign member in one plane and disposed at angles in relation to each other, and a reflector disposed rectilinearly in relation to the sign member and adapted to receive light rays projected thereto from the light source and transmit such rays to the reflecting surface of the sign member.
11. In an animated display of the class described, in combination, a reflection receiving member having an opening for passing light rays, a reflecting sign member for producing a reflection upon the receiving member aforesaid and spaced at one side thereof, a light source arranged at the opposite side of said receiving member so that rays may be projected therefrom through said opening to a reflecting surface of the reflecting sign member, said rays to be thereby projected upon the reflection receiving member, and a supplemental reflector cooperating with the light source to transmit reflected rays therefrom to the reflecting surface of the sign member and be reflected therefrom to said receiving member, said supplemental reflector being disposed at a right angle to the sign member.
12. In an animated display of the class described, in combination, a reflection receiving member having an opening for passing light rays,
- a reflecting sign member for producing a reflection upon the receiving member aforesaid and spaced at one side thereof, a light source disposed at the opposite side of said receiving member and arranged so that rays may be projected therefrom through said opening to a reflecting surface of the reflecting sign member, said rays to be thereby projected upon the reflection receiving member, a supplemental reflector disposed on the same side of the receiving member as the light source cooperating with said light source to transmit reflected rays therefrom to the reflecting surface of the sign member and then be reflected onto said receiving member, said supplemental reflector being disposed at a right angle to the sign member, and differently colored screens through which light rays from the light source are projected upon the supplemental reflector.
13. In an animated display of the class described, in combination, a reflection receiving member, a reflecting sign member for producing a reflection upon the receiving member aforesaid and spaced therefrom, a light source arranged so that rays may be projected therefrom to a reflecting surface of the reflecting sign member, said rays to be thereby projected upon the reflection receiving member, supplemental reflector means cooperating with the light source to receive light rays therefrom and reflect such rays to the reflecting surface of the reflecting sign member, said supplemental reflector means comprising a series of reflectors parallel with the sign member in one plane and disposed at angles in relation to each other, and differently colored moving screens between the light source and said reflectors so that colored rays are reflected from the reflectors to the reflecting surface of the sign member and from such surface to the reflection receiving surface of the reflection receiving member.
14. In an animated display of the class described, in combination, a reflection receiving member, a reflecting member having a predetermined outline in representation of a physical subject for producing a reflection of similar configuration upon the receiving member aforesaid and spaced therefrom, and a light source arranged so that rays may be projected therefrom to a reflecting surface of the reflecting member, said rays to be thereby projected upon the reflection receiving member.
15. In an animated display of the class described, in combination, a reflection receiving member having an opening therethrough, a reflecting member spaced therefrom and provided with a reflecting surface facing the reflection receiving member, and a light source disposed on the side of the reflection receiving member opposite that at which the reflecting member is disposed so that the rays of light from the light source may be projected to the reflecting surface of said reflecting member through the reflection receiving member opening and projected from such surface upon the adjacent face of the reflection receiving member.
16. The method of producing animated effects in sign display apparatus, which consists in projecting reflected light rays from a reflecting member having the form of a display image upon a reflection receiving member, and coloring such rays sequentially with colors of different color values as they are transmitted from the light source to the reflecting member so as to impart motion to the reflected images.

17. The method of producing animated effects in sign apparatus, which consists in projecting light rays from a light source onto an image producing a reflecting member, causing the rays 5 from the reflecting member to be received upon a reflection receiving member, and supplementing the rays with light rays projected from the light source to a supplemental reflector and thence to the said reflecting member from whence they are projected to the reflection receiving member.

18. The method of producing animated effects in sign apparatus, comprising the following

steps:—causing light rays to be projected from a lightsource directly onto an image producing reflecting member and thence causing said rays to be projected to a reflection receiving member, also causing light rays from the light source to be projected directly to a reflector supplementing the reflecting member above mentioned, and from said reflector to the reflecting member, and from thence to the reflection receiving member, and coloring said different reflected light rays as 10 they pass to the reflecting member just mentioned so as to produce animated colored images.

JAMES T. MULLEN.

CERTIFICATE OF CORRECTION.

Patent No. 2,014,660.

September 17, 1935.

JAMES T. MULLEN.

It is hereby certified that error appears in the printed specification of the above numbered patent requiring correction as follows: Page 5, first column, line 4, claim 17, strike out the article "a"; and that the said Letters Patent should be read with this correction therein that the same may conform to the record of the case in the Patent Office.

Signed and sealed this 5th day of November, A. D. 1935.

Leslie Frazer

Acting Commissioner of Patents.
